Adron P. Hammstein INVENTOR.

UNITED STATES PATENT OFFICE.

ARON BRAUNSTEIN, OF SAN ANTONIO, TEXAS.

AUTOMATIC PAPER-CONTAINER-MAKING MACHINE.

Application filed August 9, 1922. Serial No. 580,695.

To all whom it may concern:

Be it known that I, ARON BRAUNSTEIN, a citizen of the United States, residing in San Antonio, in the county of Bexar and State of Texas, have invented a certain new and useful Improvement of an Automatic Paper-Container-Making Machine; and I hereby declare the following to be a full, clear, and exact description of the invention, such as will enable others skilled in the art to which it appertains to make and use the same.

This invention relates to improvements in machines for making paper containers, and more particularly to mechanism for forming a substantially bottle-shaped paper container from a substantially conical-shaped blank.

The primary object of the invention is to furnish a machine adapted to corrugate the upper and lower portions of a substantially conical-shaped paper blank and to subsequently fold the corrugations at the lower portion of the blank to provide a cylindrical portion, and to also fold the corrugations at the upper portion of the blank and seal these last mentioned folded corrugations.

Another object of the invention is to provide instrumentalities for forming a paper receptacle of novel construction.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings:

Figure 1 is a perspective view partly in section of the complete machine.

Fig. 2 is a similar view of a shaping shell or cover forming part of the machine.

Fig. 3 is a vertical sectional view of said shaping shell.

Fig. 4 is a perspective view of a core forming part of the improved blank shaping mechanism.

Fig. 5 is a vertical sectional view of said core.

In the drawings, 5 designates a revolving drum or turn table mounted on the frame of the machine and carrying a plurality of shaping and supporting cores 5^a, four of which are illustrated for the purpose of disclosure. From the detail views of the cores shown in Figures 4 and 5, it will be seen that each core consists of a base 1 from

which extends an upwardly projecting hollow cylinder 1^a provided with radial slots 1^b. Extending upwardly from the upper edge of the cylinder, is a hollow frusto cone 2 having a cap or head 2^a provided with radially arranged slots 2^b. Arranged within the cylinder 1^a is a frusto cone 4 from which rises a post 4^a provided at its upper end with a disk 4^b from which projects upwardly extending substantially triangular shaped teeth 6 which move up and down in the slots 2^b. The cylinder 1^a is provided with arms 7 which have their upper ends pivotally connected to the cylinder. These arms move inwardly and outwardly in the slots 1^b and they are so weighted that their outer edges normally lie flush with the outer surface of the cylinder. When however, the frusto cone 4 is moved upwardly, its conical surface will engage the inner lower edges of the arms 7 and project said arms radially as shown by the dotted lines 3. During this movement the post 4^a functions to force the teeth 6 upwardly through the slots 2^b.

In manufacturing the improved containers, the blanks of conical shape are placed in inverted position on the cores, and while occupying this position on the cores, the blank is folded into the desired shape.

To accomplish the shaping of the blank, I have provided a preliminary forming shell 1^c and a final forming shell 3^a. The shell 1^c is illustrated in detail in Figs. 2 and 3, and it includes a cylinder 1^d having a bore 1^e, the diameter of which is substantially the same as the diameter of the cylindrical portion 1^a of the core. The upper end of the cylinder 1^d is provided with an inwardly extending annular flange 1^f on which rests a ring 1^g provided with a yoke 6^a. The cylinder 1^d is provided with radial slots 2^c, which when the shell is placed over the core, are adapted to receive the paper of the lower portion of the blank and the arms 7. In other words, when the arms 7 are moved outwardly, they force portions of the paper outwardly into the slots 2^c.

The ring 1^g is provided with a plurality of pivoted flaps 3^b, which are radially arranged around the ring 1^g and are spaced apart. These flaps 3^b are connected by links 4^c to a disk 5^b, and this disk is supported by a shaft 5^c that is capable of sliding vertically in the yoke 6^a.

As shown in Fig. 1, the upper end of the shaft 5^c is pivotally connected to a rocking

lever 5^a, and this lever is actuated by a link 5^e. Any suitable means may be provided for reciprocating this link. The yoke 6^a is rigidly connected to a sleeve 6^b that surrounds the shaft 5^c and the upper portion of this sleeve is provided with a pulley 6^c. The pulley is fixed to the sleeve and is driven by a belt 7. In order to permit paper blanks to be simultaneously operated upon by both the core and shell, each core, as shown in Fig. 5, is preferably provided with a depending spindle (not shown), and when the core is in a position under the shell 1^c, the spindle may be raised by any suitable means (not shown) so that the core will enter said shell. As the core moves into the shell, the lower edge of the shell will strike a lever 5^e forming part of the core, and this lever will elevate the cone 4, so that the arms 7 will be projected outwardly and the teeth 6 will be raised. As the arms 7 move outwardly they force the paper forming the lower portion of the cone shaped blank into the slots 2^c of the shell and thus form corrugations. Then the link 5^e is operated to depress the flaps 3^b, and these flaps will move downwardly between the teeth 6 and thus form corrugations at the apex of the blank. Then the core may be lowered sufficiently to release the lever 5^e and thus permit the teeth 6 and arms 7 to withdraw into the body of the cone. Then the belt 7 may be set in motion to rotate the shell 1^c and this will cause the inner surface 1^c of the shell to fold the corrugations at the lower portion of the blank and at the same time the flaps 3^b of the shell will smooth down or fold the corrugations at the pinnacle of the blank. When the blank has thus been shaped, the core may be lowered and then the turn table 5 may be shifted to bring the blank into a position beneath the final shaper 3^a. At this position, the core may be raised to bring the folded blank within the final shaper 3^a, and as this final shaper has an interior formation similar to the shape of the blank, the blank will snugly fit within the member 3^a. This member 3^a is then rotated by any suitable means in order to press the folded corrugations of the blank into a permanent position.

After the final shaping of the blank, the core is again lowered and the turn table is shifted to bring the shaped blank and the core on which it is mounted, to a position below the sealing member 4^g. This member is adapted to carry a gummed tape and means for severing this tape into small disks, which are pressed onto the folded upper end of the blank. The sealing member 4^g is supported by a rod 4^h, which is connected to one end of a rocking lever 4ⁱ that is actuated by a link 4^k.

It is obvious that the link 5^e may be oper-

ated by any suitable means but I prefer to control this operation by a lever 6^x arranged in convenient position to be actuated by the operator.

From the foregoing, it is believed that the construction, operation and arrangement of parts may be readily understood and it is apparent that various changes may be made without departing from the spirit of the invention as expressed in the claims.

What I claim and desire to secure by Letters Patent is:

1. A machine for making paper containers including a core member and a shell member, said core member having a frusto-conical shaped portion and a cylindrical portion, arms carried by the cylindrical portion and adapted to be projected outwardly, said shell member being provided with slots adapted to receive said arms when the latter are in projected position, and means for moving one of said members relatively to the other member in order to arrange the core within the shell.

2. A machine as claimed in claim 1 including means for rotating one of said members relatively to the other member.

3. A machine as claimed in claim 1 in which the pinnacle of the frusto-conical portion of the core is provided with openings, radially arranged teeth normally lying within the body of the core and adapted to be projected outwardly through said openings, and flaps connected to the shell and adapted to be moved into positions between said teeth for corrugating the end of a substantially conical shaped blank.

4. A machine as claimed in claim 1 including a cam arranged within the core and engaging said arms, and means for moving said cam to cause the arms to be projected outwardly.

5. A machine as claimed in claim 1 including a cam arranged within the core and engaging said arms for projecting the latter outwardly, a post carried by the cam, radially arranged teeth carried by the upper end of said post and adapted to be projected through the upper end of the core, and a lever for moving said cam.

6. A machine as claimed in claim 1 including a final shaping shell adapted to be occupied by the core after the blank has been shaped.

7. A machine as claimed in claim 1 including means for applying a sealing disk to one end of the blank.

8. A machine for making containers of sheet material, including a turn table, a series of core members mounted on said turn table and each having a cylindrical portion and a frusto-conical portion, radially arranged arms associated with the cylindrical portion of each core and adapted to move toward and away from the axis

of the core, radially arranged teeth adapted to project through the pinnacle of the conical portion of the core and to be withdrawn within the core, means for projecting said teeth and said arms, a first shell adapted to receive a core with a blank placed thereon and provided with slots to accommodate said arms and with flaps to cooperate with said teeth, said arms and slots being adapted to corrugate one end portion of a conical blank placed on the core and said teeth and flaps being adapted to corrugate the extremity of the other end portion of the blank, means for moving

said flaps into positions between said teeth, 15 means for rotating said shell, a final shaping shell adapted to be occupied by the blank and the core which carries the same after the blank has been corrugated and partially shaped, and means for placing a 20 sealing disk on the folding extremity of the blank.

In testimony hereof, I affix my signature in presence of two subscribing witnesses.

ARON BRAUNSTEIN.
